UNITED STATES PATENT OFFICE.

GEORGE COMSTOCK BAKER, OF ALBANY, NEW YORK.

CHECK-PROTECTOR.

SPECIFICATION forming part of Letters Patent No. 657,475, dated September 4, 1900.

Application filed September 29, 1899. Serial No. 732,060. (No model.)

To all whom it may concern:

Be it known that I, GEORGE COMSTOCK BAKER, a citizen of the United States, residing at Albany, in the county of Albany and State of New York, have invented certain new and useful Improvements in Check-Protectors, of which the following is a full and complete specification, such as will enable those skilled in the art to which it appertains to make and use the same.

This invention relates to check-protectors, and has particular relation to an improved device by which the numbers representing the amount of the check will be permanently indicated in the paper.

The object of my invention is to provide a simple and improved device of this character which will be very inexpensive and especially adapted for convenient use and for advertising purposes.

The invention is fully disclosed in the following specification, of which the accompanying drawings form a part, in which the separate parts of my improvement are designated by the same letters of reference in each of the views, and in which—

Figure 1 is a face view of a device embodying my invention. Fig. 2 is a corresponding view illustrating a slight modification. Fig. 3 is a longitudinal sectional view taken on the line 3 3 of Fig. 1. Fig. 4 is a transverse sectional view taken on the line 4 4 of Fig. 1. Fig. 5 is a face view illustrating a further modification, and Fig. 6 is an edge view of the construction shown in Fig. 5.

In the drawings forming part of this specification, *a* and *b* designate, respectively, two sheets or plates formed of metal or other suitable material and provided with a set of stencil perforations, as at *c*, representing figures and other devices such as are appropriately used in marking checks. The plates are hinged or connected together at their top edge, as at *d*, in any suitable or adapted manner, and in the opposite side edges are formed a series of notches or indentations *e*, relatively arranged on corresponding transverse planes and extending in a vertical series with respect to the stencil-perforations *c*, whereby said notches or indentations serve as guides in the adjustment of the check with relation to said stencil-perforations.

In operation it is only necessary to place the check between the plates *a* and *b* and in the proper or desired position, which will be indicated by the guides *e*, and then hold the check firmly in the left hand while with the right hand an ordinary pin or other convenient device may be used to punch through the paper of the check and perforate the same on the lines of the stencil-perforations, the pin being of course guided by the latter in the operation just described. The operation of perforating with the pin is preferably carried out with a rapid movement working the pin back and forth until the paper of the check is destroyed within the outlines of the stencil figures. The check can then be removed and readjusted in position and subsequent stencil figures punched in the same manner, as desired.

In ordinary practice the stencil-perforations *c* may be arranged to occupy substantially the whole area of the sheet or plate, said stencil-perforations being arranged in series on cross-lines extending one above the other, as shown in Fig. 1 of the drawings.

In Fig. 2 I have illustrated a slight modification, in which the stencil perforations *c* are arranged at the lower portion of the plate, leaving a free space at the top portion, as at *s*, upon which suitable advertisements may be printed. This construction, as illustrated in Fig. 2, is also adapted for punching the check-paper at either its top or bottom, the top space just mentioned serving to enable the body of the check to be inserted up between the plates *a* and *b*, so that its lower edge portion will come within the line of the first row of stencil perforations.

In Figs. 5 and 6 I have illustrated a further modification, in which a paper-cutting blade *p* projects from one of the body sheets or plates of the device. This blade may be secured to its carrying sheet or plate or it may be an integral part thereof, and in use as a paper-cutter the plates *a* and *b*, constituting the body of the device, will serve as a handle. It will be understood, further, that in lieu of the blade *p* various articles or desk-tools may be embodied in or carried by my improved check-protecting device.

My invention, aside from its simplicity, inexpensiveness, and convenience and its adapt-

ability for advertising uses, is designed particularly to insure a great measure of safety. It is of course understood that the protection of check amounts by inks is entirely worthless. Check-protectors which cut out the figures can be evaded by using the same devices for punching out other figures from similar paper and then pasting these figures in the corresponding holes in the original check-paper. By the use of my invention the paper is partly destroyed, leaving no clean-cut edges, and consequently it is not feasible to fill in the figures, it being further apparent that the use of pasted figures in any relation with respect to my invention would be an impossibility.

Having fully described my invention, I claim as new and desire to secure by Letters Patent—

1. A check-protector of the class described, comprising two superposed plates or members between which the check is inserted, said members being provided with registering stencil-perforations formed to represent denominational symbols, substantially as and for the purpose set forth.

2. A check-protector of the class described, comprising two superposed plates or members between which the check is inserted, and each of said members being provided with registering perforations formed to represent denominational symbols, and through which and through a portion of the check therebetween, a pointed instrument operates to destroy portions of said check, substantially as and for the purpose set forth.

3. A check-protector of the class described, comprising two plates or members pivoted together at one edge of each, and each provided with registering stencil-openings formed to simulate denominational symbols, substantially as and for the purpose set forth.

4. A check-protector of the class described, comprising two superposed plates or members between which the check is inserted, and provided with registering stencil-openings formed to simulate denominational symbols, and provided at their edges with guides having a predetermined relation to said symbols, substantially as and for the purpose set forth.

5. A check-protector of the class described, comprising two plates or members hinged together at an edge of each and provided with registering stencil-openings which simulate denominational symbols, said symbols being arranged in rows transversely of said plates or members, and notches or indentations formed in the edges of said plates with a predetermined arrangement relative to said rows of symbols, whereby a check inserted between said plates or members may be guided with relation to said symbols, substantially as and for the purpose set forth.

In testimony that I claim the foregoing as my invention I have signed my name, in presence of the subscribing witnesses, this 27th day of September, 1899.

GEORGE COMSTOCK BAKER.
